ABSTRACT

A transistor detecting circuit provided with a detecting sensitivity compensation transistor circuit having a compensation transistor and a resistance circuit connected between the base and collector of the compensation transistor, said compensation transistor circuit being provided in the input circuit leading to a detecting transistor.

FIG. 1

PRIOR ART

FIG. 2

FIG. 3

TRANSISTOR DETECTING CIRCUIT

BACKGROUND OF THE INVENTION

1. Field of the Invention

This invention relates to transistor detecting circuits, and its aim is to obtain steady detection sensitivity irrespective of temperature changes.

2. Description of the Prior Art

FIG. 1 shows a typical prior-art transistor detecting circuit, to which the invention pertains. It comprises a detecting transistor TR_1 , a rectifying capacitor C_1 , a d-c block capacitor C_2 , a d-c clamp resistor R_1 for clamping the d-c component of the input signal and a collector load resistor R_2 .

In this circuit, if $Z_{in} > R_s$, where Z_{in} is the impedance with respect to the transistor TR_1 and R_s is the input impedance of a signal source E , the condition for the input signal e from the signal source E to be detected as it is impressed across the base and emitter of the detecting transistor TR_1 is expressed as

$$e \geq V_{BE}, \quad (1)$$

where V_{BE} is the potential difference between the base and emitter of the transistor TR_1 .

The voltage V_{BE} is subject to changes with changing temperature. This means that the detection sensitivity of the transistor detecting circuit of the above construction also changes with a change in temperature.

SUMMARY OF THE INVENTION

An object of the invention is to provide a transistor detecting circuit provided with a detection sensitivity compensation transistor circuit consisting of a transistor and a resistance circuit connected between the base and collector of the transistor, said transistor circuit being provided in the input circuit leading to the detecting transistor, thereby ensuring steady detection sensitivity irrespective of temperature changes.

BRIEF DESCRIPTION OF THE DRAWING

FIG. 1 is a circuit diagram showing a conventional transistor detecting circuit.

FIG. 2 is a circuit diagram showing an embodiment of the transistor detecting circuit according to the invention.

FIG. 3 is a graph showing the detection sensitivity characteristic of the circuit FIG. 2.

DESCRIPTION OF THE PREFERRED EMBODIMENT

FIG. 2 shows an embodiment of the transistor detecting circuit according to the invention. This circuit includes a transistor circuit which consists of a transistor TR_2 and resistors R_3 , R_4 and R_5 and which replaces the resistor R_1 in the prior-art circuit of FIG. 1.

In this circuit construction, if $R_3 I_1 > V_{BE2}$ where R_3 is the resistance of the resistor R_3 , I_1 is the current therethrough and V_{BE2} is the potential difference between the base and emitter of the transistor TR_2 , $R_3 I_1$ can be regarded as a constant current source.

For the input signal e to be detected by the transistor TR_1 , the following condition is required.

$$e + V_{BE2} - I_2 R_4 \geq V_{BE}, \quad (2)$$

This relation is illustrated in FIG. 3.

The inequality 2 is based on the assumption that the resistor R_5 offers infinitely high resistance and carries no current.

In the absence of the input signal e to the transistor TR_1 , the transistor TR_1 is cut off providing no base current, so that no voltage drop is produced across the resistor R_5 . In this state, the potential at point A is equal to the collector potential of the transistor TR_2 , so that the inequality 2 is satisfied.

If $V_{BE} = V_{BE2}$, the inequality 2 reduces to

$$e \geq I_2 R_4, \quad (3)$$

As is apparent from the inequality 3, the detection sensitivity does not depend upon the base-emitter voltage of the transistors TR_1 and TR_2 .

20 Since R_4 in the inequality 3 is constant, the detection sensitivity solely depends upon I_2 .

Since $I_2 = (V_{CC} - V_{BE2})/R_5$ and $I_1 = I_2(1 + 1/\beta)$ where β is the current gain of the transistor TR_2 ,

$$I_2 = (V_{CC} - V_{BE2})/[R_5(1 + 1/\beta)], \quad (4)$$

Substitution of the equation 4 to the inequality 2 gives

$$e \geq (R_4/R_5) \cdot (V_{CC} - V_{BE2})/(1 + 1/\beta), \quad (5)$$

If $\beta >> 1$, the denominator of the second factor $(V_{CC} - V_{BE2}/1 + 1/\beta)$ on the right side of the inequality 5 is substantially at unity, so that the detection sensitivity is not affected by β .

Also, if R_4 and R_5 fluctuate in the same direction, their effects cancel and have no effect on the detection sensitivity.

40 If $V_{CC} >> V_{BE2}$, fluctuation of the base-emitter voltage V_{BE2} of the transistor TR_2 has no effect.

Further, it will be apparent from the inequality 5 that the detection sensitivity can be varied by varying the resistances R_3 and R_4 .

45 As has been described, according to the invention it is possible to obtain a transistor detecting circuit having a steady sensitivity characteristic immune to the influence of temperature.

We claim;

50 1. A temperature-compensated detecting circuit comprising

a detecting transistor having its emitter and collector electrodes coupled between an output terminal and ground, the base electrode of said detecting transistor being coupled to an input terminal for receiving an input signal,

a series circuit comprising a compensation transistor and a first resistor connected between the base of said detecting transistor and ground, said first resistor having a relatively large resistance value, means for providing a constant current to the base of said compensation transistor, and

a second resistor connected between the base and collector electrodes of said compensation transistor for coupling therewith.

65 2. A detecting circuit according to claim 1 wherein detection is performed under the condition

$$e + V_{BE2} - I_2 R_4 \geq V_{BE1}$$

where e is the input signal to be detected, V_{BE2} is the potential difference between the base and the emitter of said compensation transistor, V_{BE1} is the potential difference between the base and the emitter of said detecting

transistor, R_4 is the resistance of said second resistor connected between the base and the collector of said compensation transistor, and I_2 is the current through resistor R_4 .
